J. RACLQT & C. ENDERLIN.
FEED VALVE FOR INTERNAL COMBUSTION TURBINES.
APPLICATION FILED NOV. 21, 1910.

1,086,216.

Patented Feb. 3, 1914.

UNITED STATES PATENT OFFICE.

JULES RACLOT AND CAMILLE ENDERLIN, OF ST.-MAUR-DES-FOSSÉS, FRANCE.

FEED-VALVE FOR INTERNAL-COMBUSTION TURBINES.

1,086,216.

Specification of Letters Patent.

Patented Feb. 3, 1914.

Original application filed May 2, 1910, Serial No. 558,754. Divided and this application filed November 21, 1910. Serial No. 593,552.

To all whom it may concern:

Be it known that we, JULES RACLOT and CAMILLE ENDERLIN, both citizens of the French Republic, and residents of St. Maur-des-Fossés, Seine, France, have invented new and useful Improvements in and Relating to Feed-Valves for Internal-Combustion Turbines, of which the following is a specification.

10 This invention relates to feed valves for internal combustion or explosive turbines; and is more particularly designed to operate in connection with that class of turbines described in our patent application, No. 15 558,754, filed May 2, 1910.

The object of this invention is to provide a valve for an internal combustion or explosive turbine which is adapted to convey the explosive gases from the receiver into the 20 combustion chamber.

A further object is to provide a feed valve for internal combustion or explosive turbines in which the valve is provided with positive means for preventing any back fires and consequently any explosion of the explosive 25 mixture stored up in the receiver.

Referring to the drawing, wherein similar reference numerals indicate similar parts wherever used, the figure shown is a vertical 30 central section taken through a valve, embodying our preferred construction.

Each of the valves comprises a casing 10. This casing is provided in its upper wall with a screw-threaded aperture adapted to receive 35 the seat 14 for the valve body. Upon this seat is a lower cylindrical extension or sleeve 16, which passes through the entire valve casing. This extension is provided with openings 17. A puppet valve 18, provided 40 with a head 15, is placed so as to seat against the part 14. The stem of the valve extends down through the cylindrical casing 16. Upon the stem of the valve 18, is a bell-shaped member 19, adapted to slide inside 45 the extension 16. This bell-shaped member is provided with openings 20, adapted to register with the openings 17 of the extension 16, when the valve head 15, is off of its seat 14. The valve rod is extended beyond 50 the outside of the valve casing, and is provided with the usual spring 21. The valve rod is actuated in the usual manner by a cam 1 carried by the shaft 2 of the turbine.

The function of the member 19, upon the valve shaft 18, is to prevent any back fire or 55 return of any burning gas into the receiver. This is accomplished in the following manner. The bell-shaped member 19 forms with the extension 16, a slide valve. In case the valve head 15 is not tightly seated, the parts 16 and 19 are so arranged that the ports 17, between them are closed before the valve head 15 seats. Should there be any back fire when the valve head 15 is slightly off of its seat, the gases will not return to the receiver, but will be stopped within the cylindrical extension.

When the cylinder of the engine is charging, the charge is taken in through the ports 17, at the time when the ports 20, register 70 therewith, upon the upward stroke of the puppet valve. A cock 22, is provided in the intake extension 11, which allows of the feed valve being cut off from the source of supply.

What we claim as new and desire to secure 75 by U. S. Letters Patent, is:-

A valve structure of the type set forth, comprising a valve casing having an inlet connection at one side thereof and a chamber at one end thereof, a valve seat threaded into 80 the end of the casing adjacent said chamber, and having a coaxial sleeve integral therewith and extending through the casing, the sleeve having gas admission openings through which the gas passes directly from 85 the inlet connection, a valve body coaxing with said seat, a rod carrying the valve body and extending axially through and beyond the sleeve and the casing, and a cup-shaped member fixed on the rod and movable therewith, said member having a diameter which corresponds to the internal diameter of the sleeve and having openings adapted to register with said first named openings in the 90 open position of said valve body, and being 95 so disposed as to pass wholly out of registry with said openings before the valve body, in its closing movement, comes upon its seat.

In testimony whereof we have hereunto set our hands in presence of two witnesses,

JULES RACLOT.
CAMILLE ENDERLIN.

Witnesses:

H. C. COXE,
JOHN BAKER.
